(57) **CLAIM**

We claim the ornamental design for a pump component, as
shown and described.

DESCRIPTION

FIG. 1 is a top perspective view of a pump component of our
new design;

FIG. 2 is a rear elevation view thereof;

FIG. 3 is a front elevation view thereof;

FIG. 4 is a top plan view thereof;

FIG. 5 is a bottom plan view thereof;

FIG. 6 is a right-side elevation view thereof; and,

FIG. 7 is a left-side view thereof.

The broken lines in the drawings depict portions of the pump
component that form no part of the claimed design.
